FOREIGN PATENT DOCUMENTS

AU 143671 4/2001

Primary Examiner—Jeffrey Asch

(74) Attorney, Agent, or Firm—Banner & Witcoff, Ltd.

(57) **CLAIM**

The ornamental design for a key arrangement for a handset, as shown and described.

DESCRIPTION

FIG. 1 is a top view of a key arrangement for a handset showing my new design; and,

FIG. 2 is a perspective view thereof.

The broken line showing of the remainder of the handset is for illustrative purposes only and forms no part of the claimed design.
